APPARATUS FOR MOISTENING STENCIL
CARD BLANKSHarmon P. Elliott, Watertown, Mass., assignor
to Elliott Addressing Machine Company, a cor-
poration of Massachusetts

Application October 24, 1932. Serial No. 639,172

9 Claims. (Cl. 91—38)

This invention is designed to provide a simple apparatus in which a stack of paper stencil blanks in card form may be placed and successively moistened before being removed for the purpose of making them into stencils by cutting or indenting them on a typewriting machine.

Many millions of stencils are annually made for use in addressing machines, such stencils being in the shape of small cards having a rectangular frame of pasteboard or cardboard to which is pasted or cemented a strip of Yoshino paper which has been coated with a suitable composition which when damp can be partially displaced by the blows of the type in a typewriting machine so as to indent the type characters in said coating and remove portions of said coating at such points, thereby rendering those portions of the coated paper permeable to ink so that a true stencil is produced.

Heretofore it has been customary for the operator or typist forming the stencils as above described to moisten the blanks with a sponge, or damp roller, or otherwise, before putting them in the typewriting machine, but this operation consumes a certain amount of time and the degree of moistening thereby produced is not uniform and not always of the correct degree. The present invention supplies a simple, portable piece of apparatus in which a stack of such stencil blanks may be placed and the moistening of the bottom blank in the stack evenly effected while the typist is cutting another blank to form a stencil. On removal of each moistened blank from such holder the next one is brought into contact with the moistened pad beneath, and its moistening in turn can be effected while the blank just removed is being cut to form a stencil containing a name and address or other legend.

The best form of apparatus at present known to me embodying my invention is illustrated in the accompanying sheet of drawing in which

Fig. 1 is a longitudinal, vertical section of the apparatus taken on the irregular line 1—1 of Fig. 2.

Fig. 2 is a plan view of the same.

Fig. 3 is a detail end elevation with parts broken away showing the apparatus for pushing the bottom blank part way out from the holder, as indicated in broken lines in Fig. 2, and

Fig. 4 is a diagrammatic detail showing parts of said apparatus in the position assumed when the holder is raised to partially eject the bottom stencil blank into the position indicated in broken lines in Fig. 1.

Throughout the drawing like reference figures indicate like parts.

The particular apparatus here shown as constituting an embodiment of the invention consists of four main elements; a base member, indicated generally by 1, carrying the moistening means; a holder for a stack of the stencil blanks, indicated generally by 2, which has an opening at the bottom exposing the stencilizable surface of the bottom blank in the stack so that it may rest on the pad or other moistening means carried by the base member; a hinge mechanism, indicated generally at 3, connecting the base and holder so that the latter may be swung up away from the moistening means; and a pusher mechanism, indicated generally at 4, for automatically forcing one end of the bottom blank outside the holder whenever the latter is raised, thereby enabling the operator to easily grasp the protruding end of the moistened blank and pull it out for insertion in a typewriting machine to form a stencil therefrom. The details of construction of these four elements may be varied so long as they cooperate in substantially the manner to produce substantially the results hereinafter to be described.

The base member comprises a tank 5 containing water 11 and posts 6, 6a, which support a table 8 for a moisture-holding pad. 10 is a sheet of chamois leather which may rest on said table with its ends reaching down into the water 11. 85 Table 8 is held on posts 6, 6a, by dowels 9, 9a, which are of different diameters so that the table can not be mounted in a reverse position. The top of tank 5 is nearly all open leaving only side strips 17, 17. At one end is the bracket 12 supporting the perforated lugs 13, 13, in which is mounted the hinge shaft or pintle 21 for the swinging hinged element 19. 14 is an upwardly extending plate spring fastened to brackets 12 by screws 15, 15, and having a curved upper free 95 end. 16 is a downwardly extending lug from the under side of bracket 12 into which a pin 36 is screwed.

The holder for the stack of stencil blanks 40 and a hinge mounting therefor comprise a skeleton magazine formed by the four grooved uprights 26, 26, having feet 29 which are fastened by screws 39 to the parallel, horizontally extending bars 18, 18, each of which is fastened at one end by screws 20, 20, to the hinge member 19, 105 which swings on pintle 21. The other end of parallel bars 18, 18, are connected together by the cross bar 23 which is fastened to their under surfaces by some of the screws 39. Along the lower portions of the inside edges of the parallel 110

- bars 18, 18, are inwardly extending ledges 25, 25 (see Figs. 1 and 4) which underhang the side edges of the bottom blank and lift it, and the stack of blanks above it, when the holder is swung up on its hinge. On one end of pindle 21 is a knurled enlargement or head 22 which may be grasped for pulling out the pindle when the holder and base member are to be separated.
- 10 The rib 27 formed by the edge of the hinge member 19 cooperates with the curved face of spring 14 to retain the blank holder in raised position with yielding pressure, as indicated in Fig. 4.
- 15 The pusher mechanism comprises the thin slide 30 moving in oppositely disposed grooves 24, 24, in the ends of the inner faces of the parallel bars 18, 18, as shown in Fig. 3, (which slots are so located that the slide 30 will strike the end of the bottom blank in stack 40 when moved toward the latter, but will slip under the rest of the stack of blanks), together with mechanism for automatically reciprocating said slide as the blank holder is automatically raised or lowered. For this purpose I provide a bell-crank 31 pivoted at 32 on lug 35 depending from hinge member 19. The ends of this bell crank are slotted at 38 to engage a pin 36 set in lug 16, as before described, and at 37 to engage pin 34 set in ears 33, 33, projecting from the rear edge of slide 30. The lug 43 on the front edge of bell-crank 31 strikes the wall of tank 5 when the blank holder has been lifted a certain distance, as shown in Fig. 4, and thereby serves as a stop against further upward movement of said holder.
- 35 A weight 41 may be placed as a follower on top of the stack 40 of stencil blanks in the magazine.
- In operation, the water 11 soaks up into the portion of the chamois 10 resting on the table so that the latter may supply moisture to the stencilizable portion of the bottom blank resting on it when the parts are in the position shown in full lines in Fig. 1. When the operator is ready to cut or indent this dampened blank to form a stencil he swings the blank holder upward on hinge pindle 21, as by grasping the projecting end 28 of one of the bars 18. This moves the pusher mechanism into the position shown in Fig. 4, thereby shoving the moistened blank part way out of the magazine, as indicated in dotted lines at 42 in Fig. 1, so that the operator then grasps the protruding end and pulls the moistened blank all the way out and transfers it to the typewriting machine. The bottom blank can be thus forced out because there is a free space left between the bottom ends of magazine uprights 26 and the upper surface of cross bar 23.
- 60 When the operator lets go of the holder to thus withdraw the blank the holder is held in tipped-up position by spring 14, as indicated by broken lines in Fig. 1, until forced downward to start the moistening of the next blank now at the bottom of the stack, which moistening can be accomplished while the first blank is being cut or stencilized. If these operations are interrupted, the holder should be left in raised position so that no excessive moistening of the bottom stencil blank may occur from prolonged contact with the moistening pad.
- 65 Other forms of pusher mechanism and of means permitting upward movement of the blank holder, and other forms of moistening devices could be substituted for those shown, so long as they cooperate in substantially the man-

ner above described to produce the results above set out.

If, however, the stencil blanks are dropped on the flat surface of the moistening pad in such manner that contact is effected at once throughout the entire areas of the meeting surfaces, air is apt to be trapped at points more or less remote from the borders of the pad and uneven moistening results. To avoid this I prefer to have the initial contact established at one end or edge of the pad and extended gradually from that line across or along the contacting surfaces. For this reason I make the end of pad table 8 nearest the hinge pindle 21 slightly higher than the other end, as shown in Fig. 1. The bottom stencil blank therefore first strikes the chamois at that end as the holder 2 swings down and the area of contact is thereafter gradually extended to the other end of the blank, all air being driven out toward that other end as the line of contact advances.

When hinge pindle 21 is removed, the stencil holder and pusher mechanism can be lifted as a unit from base member 1 as the slot 38 permits bell-crank 31 to slip away from pin 36. The chamois 10 can then be adjusted, and water 100 poured in the tank 5 before the parts are reassembled.

A slight curvature of the particular stencil blanks here shown also contributes to their progressive contact action with the moistening pad. This curvature results from a continuous strip of the blank frames having been wound on a drum of large diameter in the manufacturing process. The convex surface so produced is on the under side of each blank in the magazine 110 stack. The supporting ledges 25, 25, are slightly bowed downward to accommodate this curvature as shown in broken lines at 25a in Fig. 1.

Having described my invention, I claim:

1. An apparatus for successively moistening each one of a stack of card shaped paper stencil blanks, or like articles comprising, in combination, a base member having a compartment adapted to hold water and a water absorbing pad therein having an exposed upper surface, a superposed magazine for a stack of such blanks which is open at the bottom so as to permit the bottom one to rest on said pad, but which has inwardly extending ledges along its opposite sides underhanging the edges of said bottom blank so as to lift said stack with said magazine if the latter is raised, a pusher mounted to slide along said ledges at one end thereof and engage the bottom stencil blank resting thereon, a hinge connecting said magazine and base member having its axis extending at right angles to said ledges and somewhat offset from said magazine, a yielding friction mechanism engaging said magazine to hold it in raised position after it has been swung up on said hinge, and mechanism for moving said pusher and the bottom stencil blank along said ledges away from said hinge whenever the magazine is swung upwardly thereon; whereby said bottom card, after being lifted away from said pad, is automatically slid along said ledges part way out of the magazine.

2. The combination of a moisture-containing base member, a vertically movable holder for a stack of card stencil blanks located over a moisture containing surface of said base member 145 so that the under face of the bottom stencil blank will rest on said surface when said holder is in its lowermost position, and mechanism automatically forcing such bottom stencil blank endwise partly out of said holder when the latter is 150

raised sufficiently to remove said blank from contact with said moisture-containing surface.

3. A combination such as defined in claim 2 in which said holder comprises a magazine rec-
5 tangular in horizontal cross section, open at the top for the introduction of a stack of stencil blanks, and having a pair of inwardly projecting ledges extending along the bottom of its oppo-
10 site sides on which the edges of the bottom blank may rest, said holder being hinged to said base along a line offset from one end of said pair of ledges and having an opening at the other end thereof through which the bottom stencil blank may be slid outwardly.

15 4. An apparatus such as defined in claim 2 combined with yielding pressure means for retaining said holder in raised position.

5. A vertically movable holder for a stack of card shaped stencil blanks having a bottom open-
20 ing exposing the stencilizable portion of the bot-
tom blank in said stack, combined with moisten-
ing means on which said portion of said bottom blank rests when said holder is lowered, and
25 mechanism for automatically pushing said bot-
tom blank part way out from said holder when the latter is raised.

6. The combination with a swinging holder for a stack of cards, a base member to which said holder is hinged, a card pusher mounted to slide
30 in said holder, and a bell-crank slotted at its

ends and pivoted on said holder, said slide carry-
ing a pin engaging one of said slots and said base carrying a pin engaging the other, together with stop means for preventing said pins being moved out of said slots.

7. A combination such as defined in claim 6 in which said stop means comprises a portion of said bell-crank and a portion of the base mem-
ber against which said bell-crank is forced by the movement of said holder.

8. An upwardly movable holder for a stack of card shaped stencil blanks having a bottom open-
ing exposing the stencilizable portion of the bot-
tom blank in said stack, combined with moisten-
ing means on which said portion of said bottom blank rests when said holder is lowered, the sur-
face of said moistening means lying in a plane
extending at an angle to the surface of said bot-
tom blank at the moment of initial contact therewith.

9. A combination such as defined in claim 8 in which said holder has a hinged support at one end, and in which said moistening means comprise a flat surface so adjusted that the por-
tion thereof nearest said hinge first makes con-
tact with the stencil blank when the holder con-
taining said blank is swung downward upon the
pad.
